John J. Adams

UNITED STATES PATENT OFFICE.

MARIUS LATOUR, OF PARIS, FRANCE, ASSIGNOR TO LATOUR CORPORATION, OF JERSEY CITY, NEW JERSEY, A CORPORATION OF DELAWARE.

VACUUM-TUBE RELAY.

Application filed August 19, 1921, Serial No. 493,674, and in France December 12, 1918.

(GRANTED UNDER THE PROVISIONS OF THE ACT OF MARCH 3, 1921, 41 STAT. L., 1313.)

This invention relates to improvements in the use of dynamos for supplying current to the filament and plate circuit of vacuum tube relays.

5 Referring to the drawings, Figure 1 illustrates an embodiment of the invention as applied to a system for supplying current to the filament and plate circuits of a vacuum tube.

10 Figure 2 illustrates a filter system which may be used in conjunction with the current supply system.

According to the present invention, a direct current machine is used and comprises 15 a commutator provided on each side of the armature and in addition, collector rings are used, as shown in Fig. 1. The first collector 1 of relatively low tension supplies current to the filaments 3. In order to increase the current tension and thus to reduce 20 the losses at the collector 1, the filaments of the vacuum tube relays of the same amplifier are preferably connected in series. This is contrary to the general practice according to 25 which the filaments are connected in parallel. The secondary winding of the transformer of each amplifying stage may be as a matter of fact connected independently and without special complications to the proper pole of 30 the filament of the tube which it actuates.

A second collector 2 of relatively high tension supplies current to the plate circuit 4 of the vacuum tube relay.

In order to avoid variations in voltage 35 which may cause noises in the amplifier precautions should be taken in the construction of the dynamo (slanting the slots, dividing into large sections, etc.), and in addition self induction coils are connected in series 40 and capacities in shunt with the output circuit.

This latter is preferably accomplished in the manner illustrated in Fig. 2. A capacity 7 is connected directly in shunt with the 45 brushes. A double wound self induction coil 8 is connected in series with the output circuit which is also shunted by a capacity 9. The invention also extends to the use of the same arrangement for the low voltage collector. This is desirable as every small heat 50 variation effects a variation in the emission

of the filaments and causes current variations in the plate circuit. Furthermore, a floating battery 5 is provided to aid in equalization, thereby preventing variations 55 in the filament current which would result in hum or noise. This battery can be used to drive the dynamo as a dynamotor in the event that the normal source fails. By means of the rings 6, connections may be 60 made to an alternating current circuit so that the device may function as a rotary converter for the purpose of charging this battery. Furthermore, when the power source fails at which time the dynamotor 65 is driven from the battery, these rings may make possible the use of the dynamo as a signaling or ringing current source in the event that the apparatus and circuits of Fig. 1 are employed in a telephone system. 70

In order to avoid losses due to the excitation of the dynamo, quite often it will be advisable to use a permanent magnet field for the dynamo. The driving motor (not shown) may be an electrical, hydraulic or 75 any other motor.

Having described my invention, what I claim is:

1. In a vacuum tube system, a plurality of vacuum tubes provided with filaments and anodes, a generator having a low voltage output and a high voltage input, means including an external source of power normally serving to drive said generator, a battery connected across the output of said generator, filaments energized from said low voltage output, said high voltage output serving to supply voltage to said anodes, said generator being arranged to be operated from said battery when said power source is not used.

2. In an arrangement for supplying heating current and space current in an electron discharge tube system, mechanism for generating a direct current of low voltage and 95 a direct current of high voltage, said direct currents each having an alternating current component, means for normally operating said mechanism, a current storing device for filtering out the alternating current component of said low voltage direct current, and a filter for filtering out the alternating 100

current component of said high voltage direct current, said current storing device functioning to operate said mechanism, when said operating means is not used.

5 3. The combination with the electrodes of an electron discharge system requiring direct currents of high and low voltage, of

a battery for supplying said low voltage currents, a machine for supplying said high voltage current, said machine being operable 10 from said battery, and means for operating said machine to charge said battery.

MARIUS LATOUR.
